Towseend & Hales
ATTORNEY'S.

UNITED STATES PATENT OFFICE.

SAMUEL SEGAL, OF NEW YORK, N. Y., ASSIGNOR TO SEGAL METAL PRODUCTS COMPANY, INC., OF NEW YORK, N. Y., A CORPORATION OF DELAWARE.

SASH FASTENER.

Application filed January 31, 1922. Serial No. 532,967.

To all whom it may concern:

Be it known that I, SAMUEL SEGAL, a citizen of the United States, and a resident of New York, in the county of New York and

5 State of New York, have invented certain new and useful Improvements in Sash Fasteners, of which the following is a specification.

My invention relates to that class of devices adapted to be screwed or otherwise fastened to one member and containing means adapted to engage another member whereby said members may be held against movement.

10 15 In one of its applications the invention relates more specifically to a window sash anti-rattler or fastener by means of which a window may be tightly held against movement. The device may be fastened to a 20 slideable window sash and tightened against a second window sash or against the window frame to lock the window sash in any position, either open, closed or partially closed.

The object of the invention is the production of a device of the above character 25 which shall be simple in construction and which shall effectively and easily perform its tightening or fastening function.

Other and further objects and advantages 30 of the invention will appear from the accompanying description, the invention consisting in the novel parts and combinations thereof hereinafter more particularly described and then specified in the claims.

35 In the accompanying drawing:

Fig. 1 is a plan view of my improved sash fastener as applied to a window.

Fig. 2 is a longitudinal section on the line 2-2 of Fig. 1.

40 Fig. 3 is a vertical section on the line 3-3 of Fig. 2.

Fig. 4 is a front elevation of the clutch member.

45 Fig. 5 is a vertical section on the line 5-5 of Fig. 2.

Fig. 6 is a view similar to Fig. 3 showing a modified form of clutch member.

Fig. 6' is a front elevation of said modified clutch member.

50 Fig. 7 is a section taken through a further

modified form of clutch member on the line 7-7 of Fig. 8.

Fig. 8 is a vertical section on the line 8-8 of Fig. 7.

Fig. 9 is a section taken through a modified form of bolt member.

Fig. 10 is a top plan view of a modified form of fastener.

Fig. 11 is a vertical section on the line 11-11 of Fig. 10.

Fig. 12 is a vertical section on the line 12-12 of Fig. 11.

Fig. 13 is a vertical section on the line 13-13 of Fig. 11.

Fig. 14 is a front elevation of the clutch member of this modification.

Referring in detail to the several figures of the drawing:

1 indicates an upper window sash and 2 a lower window sash, the window pane of the upper sash being indicated at 3. Said sashes are slideable towards and away from each other in suitable guideways of a window frame 4.

The base of my improved sash fastener is 75 indicated at 5 and is provided with openings 6 therein adapted to receive screws 7 whereby the fastener may be secured to the top rail of one of the sashes as for instance the sash 2. Extending upwardly from said 80 base 5 and preferably integral therewith is a post comprising two members 8 having a space therebetween, said post members also having screw-threaded annular openings 9 extending therethrough in alignment.

10 85 Fig. 4 indicates a clutch member provided with a pin 11 slidably extending within a bore 12 in the base 5, said clutch member being supported by the post members 8 and being prevented from rotation by engagement of said 90 pin with said bore. Said clutch member is provided with a slot 13 having an upper rounded side and a lower rectangular side as indicated in Fig. 4.

14 indicates the squared shank of a bolt 95 adapted to extend loosely through the rounded part of the opening 13 in the clutch member 10 and to be received and held against rotation by the lower rectangular portion of said opening. Said shank is 100

threaded through the openings 9 of the post members 8 and it is provided with a head 15 carrying a rubber tip 16 adapted to be pressed against and frictionally engage the upper sash 1. The rear end of the shank of the bolt carries a knurled knob 17 for rotating the bolt. 18 indicates a compression spring carried by the pin 11, said spring engaging the base 5 and the clutch member 10. 10 The action of said spring tends to press the clutch member upwardly whereby the rectangular shank of the bolt will enter or be received by the rectangular portion of the slot 13 in the clutch member to securely lock 15 said bolt against rotation as shown in Fig. 3.

To release the clutch member 10 from its locking engagement with the bolt it is merely necessary to press the clutch member downwardly against the action of the spring 20 18 so that the shank of the bolt will extend loosely through the rounded portion of the slot 13 in the clutch member. The bolt may then be rotated by means of the knurled knob 17 to thread the same forwardly 25 through the post members 8 or to retract the same. When threaded forwardly the tip 16 will be pressed against the upper sash 1 so that both sashes 1 and 2 will be prevented from rattling and will be securely fastened 30 in any desired position. When the bolt has been rotated the desired distance in either direction to fasten or unfasten the sashes, a releasing of the clutch member 10 will automatically lock the bolt against further rotation 35 as the clutch member will then be forced upwardly by the action of the spring 18 and the bolt will enter the rectangular portion of the slot 13 in the clutch member.

For assisting in the tightening operation 40 of the bolt I have provided a wrench 19 provided with a slot 20 in the head thereof, said slot being similar in configuration to the slot 13 in the clutch member 10, in that its upper side is rounded while its lower side is rectangular. Normally the wrench hangs 45 on the shank of the bolt which passes loosely through the rounded portion of the slot 20 so that a manipulation of the bolt by means of the knurled knob 17 does not alter or interfere with the position of the wrench. When 50 it is desired to bring the wrench into play it is seized by its shank and pressed upwardly until the shank of the bolt is received by the rectangular portion of the slot 20. Rotation 55 of the wrench will then rotate the bolt, as is obvious, and by means of said wrench the bolt may be tightened a considerably greater degree than if the knurled knob only were used for the tightening operation.

60 In the modification illustrated in Figs. 6' and 6 I dispense with a spring and provide the clutch member 10' with a slot 13' the wall of which has a configuration the reverse of that of the slot 13 in the clutch member 10 of the preferred form, in that the

lower portion of said slot 13' is rounded while the upper portion is rectangular. Thus the clutch member becomes interlocked with the bolt by the action of gravity as the bolt is received by the rectangular portion of the slot 13'. Before the bolt may be operated the clutch member must be lifted manually so that the bolt will extend loosely through the rounded portion of the slot 13'. 70

In Figs. 7 and 8 the post 21 comprises a single member in contradistinction to the two-part member of the preferred form which post is preferably integral with a base 22. The clutch member of this modification comprises an inverted U-shaped piece 23 having slots 24 similar to the slot 13 of the clutch member 10. The post 21 extends upwardly into the space intermedate the arms of the clutch member as clearly shown in Fig. 7 and one of the arms has a pin 24' secured thereto or integral therewith which slidably enters a bore 25 in the base 22. A spring 26 is carried by the pin 24' and presses against the arm of the clutch member and against the base 22. The action of the device is precisely similar to the action of the device of the preferred form of the invention. The clutch member 23 must be pressed downwardly against the action of the spring 24 before the bolt may be operated. When the clutch member is released it is pressed forwardly by the action of said spring and the rectangular portions of the slots 24 receive the rectangular shank of the bolt to lock the bolt against further movement. 80 85 90 95 100

In the modification illustrated in Fig. 9 the bolt 27 is provided with a longitudinal screw-threaded bore extending therethrough, the forward end 28 of the bolt comprising a hollow cup the edge of which performs the same function as the tip 16 in the preferred form. 29 indicates a supplemental screw-threaded bolt threading through the bore of the main bolt 27 and provided on its forward end with a tip 30 extending within the cup 28 and on its rear end with an operating knurled knob 31. The main bolt is operated in the same manner as the bolt in the preferred form, the supplemental bolt acting as additional fastening means which may be operated independently of the operation of the main bolt. When the supplemental bolt is threaded forwardly through the main bolt, the tip 30 thereof will press against the window sash 1 in an obvious manner to provide additional fastening means for holding the sashes against movement. This supplemental bolt may be used in conjunction with all forms of the invention. 110 115 120 125

In the modification illustrated in Figs. 10 to 14 inclusive, the base is indicated at 32 and the two-part post forming a portion thereof at 33. The clutch member 34 is provided with a slot 35 of a size permitting it 130

to loosely receive the cylindrical screw-threaded shank of the bolt 36, said shank being provided with longitudinal grooves 37 therein as indicated. The clutch member 34 is also provided with a projection 38 adapted to enter any of said grooves 37 to prevent rotation of the bolt. When it is desired to rotate the bolt the clutch member is pressed downwardly, as in the preferred 10 form of the invention, against the action of the spring 39 to release the projection from its locking engagement with one of the grooves 37. The release of the clutch member automatically locks the bolt against further movement, as is obvious, as the projection 38 will automatically enter one of said grooves 37 by the action of the spring. In this modification the wrench is indicated at 40 and is provided with an opening 41 therein through which the bolt loosely extends. When it is desired to use the wrench it is pressed upwardly so that a projection 42 thereon will enter one of the grooves 37.

It will be understood that in some cases I 25 prefer to mount and fasten the device on a sash in a position at right angles to that shown and described whereby the end of the bolt will be forced into locking engagement with the side of the window frame instead 30 of with a second sash so that the fastener when in operative position, will hold against movement only the sash to which it is secured while permitting freedom of movement of the other sash if one obtains.

35 What I claim as my invention is:

1. In a device of the character described, the combination with a base secured to a member, of a rotatable bolt associated with said base and adapted to engage a second 40 member and a clutch member for locking said bolt against movement.

2. In a device of the character described, the combination with a base secured to a member, of a post connected to said base 45 and provided with an opening therein, a rotatable bolt extending through said opening and adapted to be pressed against a second member and a clutch member for locking said bolt against movement.

50 3. In a device of the character described, the combination with a base secured to a member, of a post connected to said base and provided with an opening therein, a clutch member provided with an opening 55 therein and a bolt extending through said openings and adapted to be pressed against a second member, said clutch member being adapted to lock said bolt against movement.

60 4. In a device of the character described, the combination with a base secured to a member, of a post connected to said base and provided with an opening therein, a clutch member provided with an opening 65 therein and a bolt extending through said openings and adapted to be pressed against

a second member, said clutch member being capable of movement at right angles to the direction of movement of said bolt and being adapted to lock said bolt against movement.

70

5. In a device of the character described, the combination with a base secured to a member, of a post connected to said base and provided with an opening therein, a bolt extending through said opening and adapted to be pressed against a second member and a clutch member carried by said bolt for locking the same against movement at right angles to the direction of movement of said bolt.

75

6. In a device of the character described, the combination with a base secured to a member, of a post connected to said base and provided with an opening therein, a bolt threading through said opening and adapted to be screwed against a second member and a clutch member carried by said bolt for locking the same against movement.

80

7. In a device of the character described, the combination with a base secured to a member, of a rotatable bolt associated with said base and adapted to engage a second member, a clutch member and spring means normally holding said clutch member in interlocked engagement with said bolt to prevent rotation thereof.

85

8. In a device of the character described, the combination with a base secured to a member and having a bore therein, of a post connected to said base and provided with an opening therein, a bolt threading through said opening and adapted to be screwed against a second member, a clutch member provided with an opening through 100 which said bolt extends, said clutch member being supported by said post and a pin on said clutch member slidably extending within the bore in said base.

105

9. In a device of the character described, the combination with a base secured to a member and having a bore therein, of a post connected to said base and provided with an opening therein, a bolt threading through said opening and adapted to be screwed against a second member, a clutch member provided with an opening through 110 which said bolt extends, a pin on said clutch member slidably extending within the bore in said base and spring means normally holding said clutch member in interlocked engagement with said bolt to prevent rotation thereof.

115

10. In a device of the character described, the combination with a base secured to a member, of a post connected to said base and provided with an opening therein, a bolt threading through said opening and adapted to be screwed against a second member, a clutch member provided with an 120

125

130

- opening through which said bolt extends and adapted to prevent rotation of said bolt and means for preventing rotation of said clutch member on said bolt.
11. In a device of the character described, the combination with a base secured to a member, of a post connected to said base and provided with an opening therein, a bolt threading through said opening and adapted to be screwed against a second member, a clutch member provided with an opening through which said bolt extends, means for preventing rotation of said clutch member on said bolt and means for holding said clutch member in interlocked engagement with said bolt to prevent rotation thereof.
12. In a device of the character described, the combination with a base secured to a member, of a post connected to said base and provided with an opening therein, a bolt threading through said opening and adapted to be screwed against a second member, a clutch member supported by said post and provided with an opening through which said bolt extends, means for preventing rotation of said clutch member on said bolt and spring means engaging said clutch member for holding the same in interlocked engagement with said bolt to prevent rotation thereof.
13. In a device of the character described, the combination with a base secured to a member, of a post connected to said base and provided with an opening therein, a bolt threaded through said opening and adapted to be screwed against a second member, a clutch member for locking said bolt against rotation and a wrench loosely hanging on said bolt for rotating the same.
14. In a device of the character described, the combination with a base secured to a member, of a post connected to said base and provided with an opening therein, a bolt extending through said opening and adapted to be pressed against a second member and a supplemental bolt carried by said first-named bolt and adapted to be pressed against the second member.
15. In a device of the character described, the combination with a base secured to a member, of a post connected to said base and provided with an opening therein, a bolt extending through said opening and adapted to be pressed against a second member and a supplemental bolt threading through said first-named bolt and adapted to be screwed against the second member.
16. In a device of the character described, the combination with a base secured to a member, of a post connected to said base and provided with an opening therein, a bolt having a hollow cupped end adapted to be pressed against a second member and a supplemental bolt threading through said first-named bolt and adapted to be screwed through the cupped end thereof and against the second member.
17. In a device of the character described, the combination with a base secured to a member and having a bore therein, of a post connected to said base and provided with an opening therein, a bolt threading through said opening and adapted to be screwed against the second member, a clutch member provided with an opening through which said bolt extends, means on said clutch member slidably extending within the bore in said base and means normally holding said clutch member in interlocked engagement with said bolt to prevent rotation thereof.

Signed at New York, in the county of New York and State of New York, this 30th day of January, A. D. 1922.

SAMUEL SEGAL.
